Primary Examiner—Bernard Ansher**Assistant Examiner—Philip Hyder****Attorney, Agent, or Firm—Nixon & Vanderhye****[57] CLAIM**

The ornamental design for a tool for making snowballs, as shown and described.

DESCRIPTION

FIG. 1 is a perspective view of a tool for making snowballs showing my new design;

FIG. 2 is a perspective view thereof, with the handles in an open position;

FIG. 3 is a left side elevational view thereof, the right side elevation being a mirror image thereof;

FIG. 4 is top plan view thereof, the bottom view being a mirror image thereof;

FIG. 5 is a front elevational view thereof; and,

FIG. 6 is a rear elevational view thereof.
